(57) **CLAIM**

The ornamental design for a collapsible bathtub, as shown
and described.

DESCRIPTION

FIG. 1 is a front, left, and top perspective view of a
collapsible bathtub, showing my design.

FIG. 2 is a rear, right, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a front, left, and top perspective view of the
collapsible bathtub of FIG. 1 shown in a folded state.

The broken lines shown in the drawings are included for the
purpose of illustrating portions of the collapsible bathtub
that form no part of the claimed design.
